UNITED STATES PATENT OFFICE.

CHARLES ALEXANDER HARRIS, OF BELLVILLE, TEXAS.

MACHINE FOR WASHING DISHES.

SPECIFICATION forming part of Letters Patent No. 289,650, dated December 4, 1882.

Application filed June 16, 1883. (No model.)

To all whom it may concern:

Be it known that I, CHARLES A. HARRIS, a citizen of the United States, residing at Bellville, in the county of Austin and State of Texas, have invented a new and useful Machine for Cleansing Dishes, Cloths, &c., of which the following is a specification, reference being had to the accompanying drawings.

10 This invention relates to machines for cleansing dishes, clothes, and other articles of that class in which the water is agitated.

15 The object of the invention is to provide a simple, inexpensive, and generally efficient machine that will perform its functions speedily, and will require but very little expenditure of operating power.

20 In the drawings, Figure 1 is a top view of my device. Fig. 2 is a vertical longitudinal sectional view of the same, giving a side view, partly broken away, of the conducting-pipe. Fig. 3 is a vertical longitudinal sectional view taken on the line of the screw. Fig. 4 is a vertical transverse sectional view taken in front of the screw-casing.

25 Referring to the drawings, A designates a vessel or tank adapted to contain the water, and of any suitable shape or construction. In this vessel is arranged a suitable conducting-pipe, B, into which the water in the tank can only find ingress at the bottom of the latter. This pipe preferably comprises a pipe, C, extending horizontally along the bottom of the tank to one corner thereof, and having a wide 30 flat mouth, D, at the center of the tank. From the horizontal section of pipe C extends a vertical section, E, to nearly the top of the vessel, where it connects with a longitudinal tube, F, that preferably inclines from the pipe 35 E, and has a closed end, G, at the side of which is provided an opening or mouth, H, and from which projects an auxiliary tube, I, that forms a bearing for the operating end of the shaft J of the Archimedean screw K, that is arranged 40 in the tube F, and has bearings L in the other and of the latter, as shown. The Archimedean screw is adapted to be operated by a crank, M, or any other suitable power, and in the case 45 of small machines, for washing dishes, &c., the

screw may be operated by clock-work. But little labor is required to operate the device, as the water has only to be raised to a limited height, its ingress being at the mouth D of the tube-section C, when it is carried by operation of the screw to the mouth H, from which it is discharged into the receptacle A. It is immaterial at what part of the vessel the mouth D is located. As herein shown, it is at the center, and this location is best adapted for small vessels, as it creates a strong suction; but in large vats for tanning hides, for bleaching, &c., the water should find ingress to the tube at one end of the vat and be discharged at the other.

50 The operation and advantages of my invention will be readily understood and appreciated. The clothes, dishes, &c., will be quickly cleansed by the action of the water and by their resistance to the same, and can suffer no damage by tearing or otherwise. In tanning, 55 the frequent handling of the hides is obviated, because the machine will serve to extract the tannin from the bark better than any other process of which I am cognizant, since the hides can be placed in the water and the 60 ground bark added as it becomes necessary to strengthen the ooze. Besides, the device is very simple and inexpensive in construction and convenient in operation.

65 I claim as my invention—
80 The combination of the vat or receptacle, the conducting-tube arranged therein, and comprising a horizontal bottom section having the flat mouth, a perpendicular section arranged at one corner of the vat, and a main 70 section extending longitudinally and inclined from the perpendicular section, and having the opening or mouth, and an Archimedean screw arranged in this main portion and having bearings at its ends, substantially as and 75 for the purpose set forth.

85 In testimony that I claim the foregoing as my own I have hereto affixed my signature in presence of two witnesses.

CHARLES ALEXANDER HARRIS.
